UNITED STATES PATENT OFFICE.

VERNON LAKE CAPWELL, OF DORRANCETON, PENNSYLVANIA.

ENGINE.

1,117,974.

Specification of Letters Patent.

Patented Nov. 24, 1914.

Application filed October 29, 1913. Serial No. 798,129.

To all whom it may concern:

Be it known that I, VERNON L. CAPWELL, a citizen of the United States, residing at Dorranceton, in the county of Luzerne and State of Pennsylvania, have invented a new and useful Engine, of which the following is a specification.

The present invention relates to improvements in engines, one object of the invention being the provision of a novel oscillatory reversible valve mechanism for a reciprocating type of steam engine, said valve being so constructed and arranged, as to be oscillated in timed relation to the piston to control the intake and exhaust of the pressure fluid to and from the power cylinder.

A further object of the present invention, is the novel construction of an oscillatory valve, and reversing member therefor, said members being constructed to telescope with the operating stems disposed in opposite directions and so arranged that the normal supply and exhaust chambers from the power cylinder remain the same at all times.

A still further object of the invention is the provision of an engine of this type provided with two oscillatory valves, the intake and exhaust chambers leading to and from the valves being superposed so that the natural drain of condensation will be entirely through the exhaust chamber and outlet, said valves being so arranged that regardless of the movement of the piston, the two chambers remain at all time respectively, the supply and exhaust for the engine.

A still further object of the present invention, is the provision of an actuating valve provided with a horizontal partition, whereby the exhaust steam is prevented from entering the live steam chamber.

A still further object of the invention is the provision of a novel form of reversing valve, which is provided with air ports that produce a ventilating means for the engine when the engine is running "empty."

With the foregoing and other objects in view which will appear as the description proceeds, the invention resides in the combination and arrangements of parts and in the details of construction hereinafter described and claimed, it being understood that changes in the precise embodiment of the invention herein disclosed can be made within the scope of what is claimed with-

out departing from the spirit of the invention.

In the drawings—Figure 1 is a section taken on line 4—4 of Fig. 2. Fig. 2 is a section taken on line 5—5 of Fig. 1. Fig. 3 is a plan view of one of the actuating valves. Fig. 4 is a section taken on line 7—7 of Fig. 3. Fig. 5 is a section taken on line 8—8 of Fig. 3. Fig. 6 is a view similar to Fig. 3 of the reverse valve. Fig. 65 7 is a section taken on line 10—10 of Fig. 6. Fig. 8 is a section taken on line 11—11 of Fig. 6.

Referring to the drawings, the numeral 4 designates the power cylinder which is mounted as usual and having disposed therein for reciprocation, the power piston 5 which is connected to the cross head through the medium of the piston rod 6.

The power cylinder 4 is provided with the two heads 7—7', each of which is cored as at 8—8' and provided with a plurality of ports 9, said ports being of relatively large diameter and separated or spaced, as shown in Fig. 2, so as to present the greatest possible effective jets of the pressure fluid upon the face of the piston 5.

The steam chest C of the engine, has the intake or supply conduit 10 led into one side thereof into the supply chamber 11, 85 which is separated by the horizontally disposed partition 12 from the lower exhaust chamber 13 provided with the exhaust connection 14. Thus it will be seen that the exhaust chamber being at the lowest point 90 of the chest C, will receive the draining from the condensation and thus will insure the proper drainage of the engine at all times.

The steam chest is provided with the transversely disposed supply ports 15—15' which lead from the chamber 11 into the transversely disposed cylindrical bores 16—16' which are open at their ends and thus permit of the proper introduction 100 therewithin of the reversing and actuating valves, to be described presently.

The channels 17—17' are led from the respective cylindrical bores 16—16' into the lower end of the cored portions 8—8' of the head, and thus provide the means whereby the pressure fluid is conducted to and relieved from the power cylinder to produce the desired reciprocation of the power piston 5.

The reversing valve 18, there being two in the present structure, is insertible through one end of its respective bore 16—16', and has attached at its sealed head, an operating 5 stem 19, the disk 20 being connected thereto by any well known means, while the cap 22 carrying the stuffing box also provides an air space or chamber 21 adjacent the head of the valve 18 and the adjacent portion of 10 the stem 19, thus insuring the proper cooling of the valve at this point. This valve is divided centrally and one portion around the partition is provided with three ports 23 and the other portion is provided with four 15 ports 24 and the lubricating or air directing ports 25. The ports 23 are formed in quartering relation to each other, the opposite sides of the central port being blank, while the ports 24 are disposed in quartering relation with the ports 25 at diametrically opposite points relative to each other.

Disposed to oscillate within and be telescoped by its respective reversing valve 18 and insertible through the open end of the 20 valve 18 and the opposite end of its respective bores 16—16' of the steam chest C, is the actuating valve 26, the same being divided centrally by means of the partition 27 into two chambers, each of said chambers 25 being further divided by means of the curved deflecting plates 28—28' so as to constitute an intake and exhaust chamber in each one of the respective ends of the valve. The intake compartment of the valve 26 is 30 provided with the two ports 29—29', which are disposed to be alined with the ends of the respective channels 15 and 17 or 15' and 17' so that the pressure fluid will be admitted from the chamber 11 through the port 40 29 into the chamber of the valve and finally through the port 29' to the desired end of the power cylinder. As shown in Fig. 1, the pressure fluid follows the course of the arrows, and being admitted from the cored 45 chamber 8' and the ports 9 will move the piston from right to left. The exhaust chamber of the valve is provided with the respective ports 30—30' which are disposed to form communication between one of the 50 channels 17—17' and the respective ports 18' leading into the exhaust chamber 13.

The sealed end of the valve 26 has attached thereto, the disk 33 of the stem 31, said stem 31 being disposed through the 55 stuffing box carrying casing 32 which provides the air chamber 34, similar to the chamber 21 at the opposite end, thus providing means for maintaining the stem and sealed end of the valve 26 cool.

60 In order to permit of the proper operation of the present engine, and to control the distance of oscillation and the position of the respective controlling valves, the two stems 31 of the actuating valves are each provided 65 with the crank (not shown). By this means,

the two valves are operated as usual from the cross head (not shown).

It is apparent that the lubricant may be supplied with the steam in the ordinary manner, but by drawing lubricant through the channel 50, to the respective valve there is no carbonizing of the lubricant and therefore the contacting surfaces of the valves remain smooth and are properly lubricated at all times.

70 From the foregoing description, it is evident that with the controlling and reverse valves arranged as herein shown, that steam is economized and that the respective sealed ends of the valves as clearly shown in Fig. 2, are properly cooled due to the air chambers 21 and 34, and that by reason of the arrangement of the respective chambers 11 and 13, the drain due to condensation and other reasons both when the engine is running and at a standstill, will be by gravity 80 and into the exhaust chamber 13. By this form of valve, it will also be seen, that the intake chamber 11 remains at all time the intake chamber regardless of the position of the reversing valve 18 and that therefore the chambers are not interchanged as is the custom in the usual oscillatory and reciprocating valves.

85 The ports 29—29', there being four to each valve 26, are so arranged as to not interfere with the admission of the pressure fluid, the same being positioned, as clearly shown in Figs. 4 and 5, so that while one side is forming communication with the desired end of the cylinder, the ports at the opposite side of the valve are closed.

90 What is claimed is:

1. An engine, the steam chest of which is provided with superposed inlet and exhaust 105 chambers and two transversely disposed valve compartments, said inlet and exhaust chambers being in communication with said valve compartments, two controlling valves, one mounted in each valve compartment, 110 each one of said valves being a hollow cylindrical member having a longitudinal partition forming an inlet and an exhaust chamber in the valve, said steam chest being provided with channels leading from 115 the valve compartments to supply pressure fluid to the power cylinder, means for simultaneously oscillating the two valves to alternately shift the relative positions of the inlet and exhaust chambers of the valves, 120 and two reversing valves one to each controlling valve for regulating the direction of the pressure fluid.

2. An engine, the steam chest of which is provided with superposed inlet and exhaust 125 chambers and two transversely disposed valve compartments, the inlet and exhaust chambers being in communication with said valve compartments, two controlling valves, one mounted in each valve com- 130

- partment, each one of said valves being a hollow cylindrical member having a longitudinal partition forming an inlet and an exhaust chamber in the valve, said steam chest being provided with channels leading from the valve compartment to supply pressure fluid to the power cylinder, means for simultaneously oscillating the two valves to alternately shift the relative positions of the inlet and exhaust chambers of the valves, two reversing valves one to each controlling valve for regulating the direction of the pressure fluid, and means for controlling both of the reversing valves in unison.
3. An engine, including a power cylinder, a steam chest provided with superposed inlet and exhaust chambers and two transversely disposed cylindrical valve receiving bores, said chest being further provided with two ports leading from the inlet chamber to the respective valve receiving bores and two ports leading from said bores to the respective ends of the power cylinder, two tubular controlling valves insertible into the respective transverse bores of the steam chest for oscillation, each of said valves being provided with intake and exhaust ports causing communication between the inlet chamber and the end of the power cylinder, and with the respective ends of the power cylinder and the exhaust chamber, and two reversing valves mounted exteriorly of each controlling valve, and provided with ports for regulating the admission of pressure fluid to the controlling valves.
4. An engine, including a power cylinder, a steam chest provided with superposed inlet and exhaust chambers and two transversely disposed cylindrical valve receiving bores, said chest being further provided with two ports leading from the inlet chamber to the respective valve receiving bores and two ports leading from said bores to the respective ends of the power cylinder, two tubular controlling valves insertible into the respective transverse bores of the steam chest for oscillation, each of said valves being provided with a longitudinal partition dividing the same into an inlet and an exhaust chamber, and each of said chambers being provided with two ports, the ports of the inlet chamber being disposed for registration with the ports leading from the inlet chamber of the steam chest to the channel leading to the end of the power cylinder while the ports of the exhaust cham-

ber are disposed for registration with the channel leading from the power cylinder to the port leading into the exhaust chamber, and two reversing valves, one mounted exteriorly of each controlling valve, and provided with ports for regulating the admission of pressure fluid to the controlling valves.

5. An engine, including a power cylinder, a steam chest provided with superposed inlet and exhaust chambers and two transversely disposed cylindrical valve receiving bores, said chest being further provided with two ports leading from the inlet chamber to the respective valve receiving bores and two ports leading from said bores to the respective ends of the power cylinder, two tubular controlling valves insertible into the respective transverse bores of the steam chest for oscillation, each of said valves being provided with intake and exhaust ports causing communication between the inlet chamber and the end of the power cylinder, and with the respective ends of the power cylinder and the exhaust chamber, and two reversing valves mounted exteriorly of each controlling valve, and provided with ports for regulating the admission of pressure fluid through the controlling valves, said reversing valves each being provided with additional ports of lesser diameter than the controlling ports, said ports forming air admitting means to ventilate the engine when pressure fluid is not being admitted thereto.

6. An engine, the steam chest of which is provided with a transversely disposed cylindrical bore open at both ends, said bore having leading therefrom three ports, two hollow cylindrical members fitting telescopically with relation to each other and insertible through opposite ends of the bore and constituting controlling and reversing valves for the steam chest, an operating stem carried by each valve one stem upon each side of the steam chest, and two caps, one cap secured to each side of the steam chest and surrounding the stem to provide an air space adjacent the head of its respective valve and the stem.

In testimony that I claim the foregoing as my own, I have hereto affixed my signature in the presence of two witnesses.

VERNON LAKE CAPWELL.
